ALBERT A. PAULY, OF YOUNGSTOWN, OHIO, ASSIGNOR TO THE CONCRETE STONE AND SAND COMPANY, OF YOUNGSTOWN, OHIO, A CORPORATION OF OHIO.

PROCESS OF MAKING ARTIFICIAL-STONE ARTICLES.

965,007.

Specification of Letters Patent. Patented July 19, 1910.

Application filed July 8, 1908, Serial No. 442,525. Renewed June 3, 1910. Serial No. 564,858.

To all whom it may concern:

Be it known that I, ALBERT A. PAULY, a citizen of the United States, residing at Youngstown, in the county of Mahoning and State of Ohio, have invented or discovered new and useful Improvements in Processes of Making Artificial-Stone Articles, of which the following is a specification.

10 My invention relates to the molding of cement or articles containing cement, having hardening or setting qualities similar to Portland cement.

It is the object of my invention to heat 15 the molded articles while in the mold so that they may be removed from the mold in a much shorter time than that required when the hardening or setting is not hastened.

To be more specific, it is the object of the 20 present invention to provide a method by which articles of uneven thickness may be heated substantially evenly.

I have shown my process in connection 25 with the molding of hollow bodies but it is not confined to the same.

Referring to the drawings accompanying this specification, Figure 1 is a vertical section of an apparatus adapted to my process, an article being shown in the mold. Fig. 2 30 is a central vertical section of the upper part of Fig. 1, showing the article ejected from the mold.

1 represents an outer molding die, having its wall double to form the jacket 2 to contain water and steam for heating the molded article 3, which is shown as a sewer pipe.

4 is a water pipe having any desired number of branches 5 leading up through the bottom of the jacket 2 and terminating at 40 or near the bottom of the bell forming, or expanded portion of the die 1. Within the pipe 4 is the steam pipe 6 having the branches 7 which stand inside the branches 5 and have their upper ends within the jacket 2 and preferably somewhat above the top of the branches 5.

8 is a hollow core standing in the die 2 and has its top closed and its lower end connected to the water pipe 4 by means of

50 the branch pipe 9. The branch steam pipe 10, connected to the steam supply pipe 6, preferably lies within the branch pipe 9 and extends preferably nearly to the top of the core.

55 11 is a ring around the upper end of the

core for forming the seat 12 of the sewer pipe.

13 is a cross-head supporting a number of stripper bars 14 which engage the underside of the article supporting ring 15. The 60 cross-head is raised by means of the chains 16 which have one end attached to the cross-head and the other end to the rotary shafts 17 and 18.

Supposing the article 3 to have just been 65 molded, the steam entering the core heats the inner portions of the article from end to end. The ring 11 prevents the steam from heating the relatively thin portion of the article above the seat 12 to so high a 70 degree as the portions below the said seat. The article being thicker in the bell below the seat 12 will not be heated or set so soon as the thinner body portion of the article below the bell.

75 Steam is introduced into the jacket 2 by means of the branch pipes 7 whose ends are preferably opposite the end of the pipe 10. The steam in the jacket heats the article 3 around the bell and assists the steam in the 80 core to harden the thicker portion of the bell. The water in the jacket being at a lower temperature than the steam prevents the article below the water line from hardening as fast as it would in case steam were 85 used entirely in the jacket. The temperature of the water and steam can be regulated to harden the sewer pipe substantially evenly from end to end. The die may be thickened, if desired, as shown at 19 to make the 90 upper end of the bell harden slower. The ring 11 and the thickened portion 19 retard the conduction of heat. This principle illustrated by the portion 19 may obviously be extended to the walls of the die or the core, 95 when it is desired to retard the conduction of the heat to the molded article.

The water in the jacket may be heated in any desired manner before or after it is admitted to the same. Ordinarily steam 100 in the jacket and core will be sufficient. The water of condensation runs down the branch pipes 5 and 9 and thence through the pipe 4.

105 The principle of my invention may be applied to the make of various kinds of articles by heating in any manner the thicker portions of the articles thereof, whether by thickened walls, or by steam and water, or otherwise.

2
I claim—

1. The process of substantially uniformly hardening molded cementitious articles of varying thickness which consists in applying to the mold surfaces fluids of different temperatures, the hotter fluid being applied to those portions of the mold adjacent to the thicker portions of the molded articles.
2. The process of substantially uniformly hardening molded cementitious articles of varying thickness which consists in apply-

ing water to those portions of the mold surfaces adjacent to the thinner portions of the article, and steam to those portions of the mold surfaces adjacent to the thicker portions of the molded articles. 15

Signed at Youngstown, Ohio, this 29th day of June, A. D. 1908.

ALBERT A. PAULY.
